(57) **CLAIM**

What is claimed is the ornamental design for a display panel of a programmed computer system with a graphical user interface, as shown and described.

DESCRIPTION

The file of this patent contains at least one drawing executed in color. Copies of this patent with color drawings will be provided by the Office upon request and payment of the necessary fee.

FIG. 1 is a front view of a display panel of a programmed computer system with a graphical user interface, showing a first embodiment of the new design;

FIG. 2 is a second embodiment thereof;

FIG. 3 is a third embodiment thereof;

FIG. 4 is a fourth embodiment thereof; and,

FIG. 5 is a fifth embodiment thereof.

The outermost broken line rectangle illustrates a display screen and forms no part of the claimed design. The remaining broken lines illustrate portions of the graphical user interface that form no part of the claimed design.
